SHOE SHANK

Filed Nov. 29, 1926

FIG. 1.

FIG. 2.

FIG. 3.

FIG. 4.

Helmer G. Josephson, ^{Inventor}

By John T. Boyle, ^{Attorney}

UNITED STATES PATENT OFFICE.

HELMER G. JOSEPHSON, OF SAUGUS, MASSACHUSETTS, ASSIGNOR TO JOHN L. SHEVENCHELL AND HELMER G. JOSEPHSON, TRUSTEES, OF MASSACHUSETTS.

SHOE SHANK.

Application filed November 29, 1926. Serial No. 151,481.

My invention relates to a metal shank adapted to be secured in the arch of a shoe during the process of manufacture and is particularly intended as an improvement on 5 the type of shank disclosed in the patent to Winchell, No. 1,447,001, dated February 27, 1923. That shank comprises a piece of struck up metal arched longitudinally and provided with a groove running lengthwise 10 thereof, but terminating short of the extremity to provide flat end portions. Teeth struck up from the end portions are provided for securing the shank to the leather.

In the manufacture of turned shoes the 15 metal shank is first applied to a leather stiffener and this stiffener is inserted into the shoe, after it has been turned, and extends from the heel of the shoe to the ball line. Some means must be provided for securely 20 holding the leather shank piece, and its attached metal shank in place in the shoe while it is being worn. Various means have been utilized with this end in view but none of them is as simple to apply or as securely 25 anchors the leather shank in position in the shoe as does mine.

In order that the invention may be more clearly understood, reference is had to the accompanying drawing in which:

30 Fig. 1 is a longitudinal section of a shoe, showing the metal shank in position.

Fig. 2 is a plan view of the metal shank.

Fig. 3 is an elevation of Fig. 2.

35 Fig. 4 is a section on the line 4—4 of Fig. 3.

The metal shank comprises a strip of cold rolled metal having a relatively deep-groove 1, running longitudinally of the body of the shank but terminating short of the ends 40 whereby there are provided flat end portions 2 and 3. Struck out from the end portion 2 are a pair of teeth 4 and struck out from the end portion 3 are a pair of teeth 5.

In order to prevent the shank from cutting 45 into the overlying leather, the sides of the groove 1 may be flared outwardly to provide substantial areas of contact such as, by means of flanges 6 running either partly or the whole length of the shank.

50 Struck out of the body of the shank from the bottom of the groove 1 and intermediate its end portions are a pair of integral teeth 7.

The shank iron having already been applied to the leather shank 8 by driving the 55 teeth 4 and 5 thereinto, the assembled piece is then placed inside the turned shoe in proper position and the teeth 7 driven into and clinched on the outer sole 9. In this manner, the leather shank 8 is securely held 60 in position against twisting or sliding in the finished shoe.

While I have disclosed the integral clinching teeth 7 in connection with the particular form of shank disclosed in the Winchell 65 patent, it is apparent that the integral intermediate teeth could be used with modified forms of the said shank.

I claim:

1. A shank iron for turn shoes comprising 70 a strip of malleable struck up metal curved longitudinally and provided with a groove terminating short of the extremities of the strip to provide flat end portions, integral clinching teeth in the end portions 75 adapted to be driven into a leather shank and an integral clinching tooth intermediate the end portions and struck out from the bottom of the groove and adapted to be driven into the outer sole. 80

2. A shank iron for turn shoes having 85 clinching teeth in its end portions for attachment to the under side of a leather shank, the said iron being curved longitudinally and provided with a groove terminating short of the extremities of the strip to provide flat end portions, and a pair of integral clinching teeth intermediate the end portions and struck out from the bottom of the groove and adapted to be driven into the outer sole. 90

3. A shank iron for turn shoes comprising 95 a strip of malleable struck up metal curved longitudinally and provided with a groove terminating short of the extremities of the strip to provide flat end portions, fastening devices in the end portions adapted to be driven into a leather shank and integral clinching teeth intermediate the end portions and struck out from the bottom of the groove and adapted to be driven into and clinched in the outer sole. 100

In testimony whereof, I have hereunto set my hand.

HELMER G. JOSEPHSON.
